VALÈRE ALFRED FYNN, OF ST. LOUIS, MISSOURI, ASSIGNOR TO WAGNER ELECTRIC MANUFACTURING COMPANY, OF ST. LOUIS, MISSOURI, A CORPORATION OF MISSOURI.

IGNITION SYSTEM.

1,216,792.

Specification of Letters Patent. Patented Feb. 20, 1917.

Application filed April 13, 1914. Serial No. 831,453.

To all whom it may concern:

Be it known that I, VALÈRE ALFRED FYNN, a subject of the King of England, residing at the city of St. Louis, State of 5 Missouri, United States of America, have invented a certain new and useful Ignition System, of which the following is such a full, clear, and exact description as will enable any one skilled in the art to which it applies 10 to make and use the same, reference being had to the accompanying drawings, forming part of this specification.

My invention relates to an ignition system for use in connection with internal combustion engines, comprising an automatic switch for changing from vibrator to single sparks and vice versa during the operation of the engine.

In the accompanying drawings, Figure 1 20 illustrates the preferred form of my ignition system in connection with an automatic switch for changing from vibrator to single sparks and vice versa; Fig. 2 shows a slight modification of the system disclosed in the 25 first figure; and Fig. 3 illustrates a further modification.

Fig. 1 illustrates an ignition system designed to operate in conjunction with a storage battery and a dynamo electric machine 30 adapted to charge the same. The storage battery 35 is permanently connected to the main brush 57 of the generator 52; the other main brush 56 of said generator is adapted to be connected to the other terminal of the 35 battery through an automatic battery switch. The generator is excited by means of the shunt winding 54 connected between the main brush 57 and the auxiliary brush 55 displaced from the main brushes. This generator 40 is driven from the explosion engine in some convenient manner. The automatic battery switch comprises an armature 58 pivoted at 59 and normally under the control of spring 60. This armature carries a 45 contact 61 adapted to coöperate with the stationary contact 62. The core 65, carrying the shunt coil 64, connected to the main brushes of the generator and the series coil 68 connected between the main brush 56 of 50 the generator and the armature 58 of the automatic switch, is adapted to attract the latter into contact with the stationary terminal 62.

The secondary ignition circuit comprises 55 the secondary 4 of the spark coil and one or

more spark gaps such as 5, 6. It is well understood that a distributor would, in general, be used between the secondary 4 and the spark gaps, but as this does not form a part of my invention, it has not been illustrated. 60

The primary ignition circuit for producing vibrator sparks comprises the storage battery 35; the primary or exciting coil 3 of the spark coil wound around the magnetic core 2; a circuit breaker comprising the stationary contact 7, the contact 8 attached to the movable arm 9, pivoted at 12, normally under the control of the spring 10, but within the range of operation of the cam 11 driven from the explosion engine and adapted to periodically lift the breaker arm 9 out of contact with the terminal 7; a timer 47 also driven from the engine, provided with a conducting plate 48 electrically connected to the breaker arm 9 and adapted to coöperate with the stationary brush 46; and a vibrator comprising a spring-mounted armature 31, pivoted at 32, carrying a contact 33 coöperating with the stationary contact 34 and under the influence of the magnet 29 80 energized by the series coil 30 connected between the vibrator armature 31 and the timer brush 46. It is seen that the circuit breaker, the timer, and the vibrator are connected in series with the battery and the spark coil.

The automatic switch 18 is so arranged that in one of its positions, it short-circuits the circuit breaker contacts 8, 7, and in its other position, it short-circuits the timer and the vibrator contacts 33, 34. This automatic switch comprises a lever 19, pivoted at 20, and held in contact with the terminal 22 by the spring 21, whereby the circuit breaker contacts are short-circuited through the 95 switch 13. An electro-magnet, having a core 27, a shunt coil 26 and a series coil 25, coöperates with the switch arm 19 and, when energized, overpowers the spring 21 and forces 19 into contact with the terminal 23, 100 thus short-circuiting the vibrator contacts and the timer contacts through the switch 13, the lever arm 19 and the series coil 25. The spring 24 is arranged to give a snap motion to the switch-lever 19. When 19 is 105 in contact with 23, the single spark circuit is established comprising the exciting coil 3, the circuit breaker contacts 7, 8, the switch 13, the lever 19 and the contact 23 and the series coil 25. This single spark circuit is 110

energized either by the storage battery 35 or the dynamo 32. The shunt coil 26 is normally connected to the main brushes of the generator through the switch 49, but can be connected at any time across the battery by placing switch 49 on point 51.

The dry cells 36 are provided for use in case the storage battery should be temporarily out of condition. When the ignition switch 42 rests on point 43, then the storage battery is in circuit with the spark coil. When said switch rests on point 44, the ignition circuit is interrupted; when it rests on point 45, then the dry cells 36 are included in a circuit with the spark coil and the circuit breaker.

The switch 13 is so located that, when open, it will prevent the automatic switch 18 from short-circuiting the circuit breaker contacts of the timer and vibrator contacts. A condenser 17 is connected across the circuit breaker contacts 7, 8, and a condenser 28 across the vibrator contacts 33, 34, for the purpose of minimizing the sparking at said contacts and for improving the operation of the spark coil.

The operation of this improved system may be briefly described as follows: Assuming the engine to be at rest and the switches 13 and 49 in the positions shown, then the circuit breaker contacts 7, 8 will be short-circuited by the switch lever 19 of the automatic switch 18 and, if the position of the timer is such that the brush 46 is not in contact with the conducting segment 48, then the engine will not be able to start on compression when the ignition switch 42 is moved from its "off" position 44 to its storage battery position 43, but the operator may make an attempt to so start the engine by depressing the key switch 40. Should the engine fail to start, then it must be cranked, either mechanically or by hand, thus causing the dynamo 52, the cam 11 and the timer 47 to revolve. The revolution of the cam 11 will periodically lift 8 out of contact with 7, but without affecting the circuit through the primary winding 3 of the spark coil because of the short-circuit around said contacts established by 19. But every time the brush 46 comes into contact with the segment 48 of the timer, the vibrator 31 will operate to produce a series of sparks, which will eventually fire the charge of the engine cylinders. After the engine has started, its speed may be increased in the usual manner and will finally reach a point at which the generator will excite. The shunt coil 26 of the automatic switch 18 is so dimensioned that when the generator voltage reaches a certain value, the magnet 27 will overpower the spring 21 and force the lever 19 into contact with the terminal 23 thereby interrupting the short circuit around the circuit breaker contacts 65 and closing the short circuit around the

timer and the vibrator. As soon as the lever 19 has moved from 22 to 23, the production of vibrator sparks will be interrupted and single sparks will be produced instead every time that the cam 11 breaks the circuit at the points 7, 8. The shunt coil 64 of the automatic battery switch is dimensioned to attract the armature 58 when the generator voltage approximately equals that of the battery, thus connecting the generator in parallel to the battery and to the primary of the spark coil through contacts 7, 8. The coil 26 may be dimensioned to close the switch 18 before the coil 64 attracts the armature 58, or it may be arranged to overpower the spring 21 at the same time that the spring 60 is overpowered. When the generator is connected in parallel with the storage battery, it not only charges the latter, but also supplies the primary ignition circuit as soon as the engine speed has risen appreciably beyond that at which the automatic battery switch has closed. It will be seen that it is quite immaterial when the short-circuit around 7, 8 is open and that around the timer and the vibrator closed. If this operation is performed when 8 is in contact with 7, then the opening of the short circuit around these contacts will obviously not have any effect, and the short-circuiting of the timer and the vibrator can only suppress the vibrator sparks, if any are being produced at the time. If brush 46 is not in contact with the segment 48 when 19 is thrown over to the terminal 23, then 19 only closes the primary ignition circuit, which operation does not produce any spark in the secondary. But it is quite important that the switch lever 19 shall not interrupt the short circuit around the timer and the vibrator at an inopportune moment. Should contact between 23 and 19 be broken when 8 is in contact with 7, during most of which time 46 will not be in contact with 48, then the primary ignition circuit will be interrupted at the point 23 and a single spark will be produced in the secondary ignition circuit at a time when such a spark is not wanted, and may produce backfiring. To obviate this difficulty, I provide the series winding 25 on the magnet 27 and so dimension the latter that the current circulating in the primary ignition circuit when 8 is in contact with 7 is sufficient to hold the lever 19 against the spring 21, even if the coil 26 is deenergized. This coil will be deenergized when the speed of the engine drops so low that the voltage generated by the dynamo is less than the terminal voltage of the battery, when the latter will send a discharging current into the generator. This current passing through the series coil 63 will oppose the magnetization produced by 64, thus releasing the armature 58 and interrupting the connection between the brush 56 and one pole of the bat-

ter 35. As soon as the generator voltage has sunk below a certain value, the holding power of the coil 26 will not be sufficient to withstand the spring 21, and the lever 19 will be released as soon as the cam has lifted 8 out of contact with 7. Should it be desired for any reason to operate the switch 18 independently of the generator, then the switch 49 can be opened and placed on point 51 whenever it is desired to pass from vibrator to single sparks. In order to return to vibrator sparks, it is only necessary to again open switch 49.

Fig. 2 differs from Fig. 1 only in that the timer 47 and the cam 11 have been combined. With the switch lever 19 in contact with the terminal 22, vibrator sparks will be produced as long as the cam 11 is in electrical contact with the circuit breaker arm 20. When 19 is in contact with 23, then single sparks will be produced every time the cam 11 lifts 8 out of contact with 7. It is not necessary or desirable for 19 to contact simultaneously with 22 and 23. In Fig. 1, 25 the timing of the first vibrator spark relatively to the single spark is entirely unrestricted, because the timer is independent of the cam and circuit breaker arm; but in Fig. 2, this relative timing is fixed, because the 30 vibrator circuit must be made through the timer cam 11 almost at the instant when 8 is separated from 7.

In Fig. 3, the automatic switch 18 is applied to an ignition system which can be 35 fed from a storage battery or a dynamo adapted to charge the latter, but in which the circuit breaker contacts 7, 8, adapted to produce single sparks, and the vibrator contacts 33, 34, adapted to produce vibrator 40 sparks, are located in parallel circuits. The automatic switch 18 renders the one or the other circuit inoperative by interrupting same instead of short-circuiting it as is the case in Figs. 1 and 2. The operation of the 45 dynamo and the automatic battery switch is as before, and the ignition switch may either interrupt the primary ignition circuits or feed the one or the other either from the battery or from the dry cells. With the 50 ignition switch 42 in the position 43 and with the spring 21 in control of the lever 19 of the automatic switch 18, the primary ignition circuit can be traced from the battery 35 through the primary 3 of the spark 55 coil to the stationary contact 34 of the vibrator, the contact 33 attached to the vibratile element thereof pivoted at 32, the energizing coil 30 wound around the core 29, the brush 46 coöperating with the timer 60 47 and periodically contacting with the conducting segment 48 connected to the terminal 23 of the automatic switch 18, through the lever 19 thereof, and back to the battery through the ignition switch 42. After the 65 voltage of the dynamo has risen sufficiently

to fully energize the coil 26 of the automatic switch, the core 27 thereof will attract the lever 19, overpowering the spring 21, and will cause said lever to break contact with the terminal 23 and to connect with the 70 terminal 22, whereby the vibrator circuit will be interrupted and the single spark circuit closed as follows: from the negative pole of the battery 35 through the primary 3 of the spark coil, the stationary contact 7 75 of the circuit breaker, the contact 8 attached to the circuit breaker arm 9 pivoted at 12, the series coil 35 on the magnet 27, the terminal 22, the switch lever 19, and back to the battery through the ignition switch 42. 80 It is preferred to arrange for the lever 19 to make contact with the terminal 22 before breaking contact with the terminal 23. Here again it is immaterial when the lever 19 leaves 23 and contacts with 22, but if 85 sparks at inopportune moments are to be avoided, then 19 must not leave 22 to contact with 23 except when the single spark circuit is interrupted at the points 7 and 8. This condition is met in the same manner as 90 in Figs. 1 and 2 by providing a series coil 25 connected in series with said contacts.

Having fully described my invention, what I claim as new and desire to secure by Letters-Patent of the United States is:

1. In an ignition system for combustion engines, a secondary ignition circuit, an exciting coil for energizing said secondary circuit, two circuit breakers for the exciting coil, one comprising a vibratile element, and means operating to continuously maintain one or the other of said circuit breakers in electrically inoperative condition. 100

2. In an ignition system for combustion engines, a secondary ignition circuit, an exciting coil for energizing said secondary circuit, a source of current for the exciting coil, two circuit breakers for the said coil, one comprising a vibratile element and each connected to the source of current, and a 105 single switch coöperating with both circuit breakers and adapted to render either circuit breaker electrically operative or inoperative. 110

3. In an ignition system for combustion engines, a secondary ignition circuit, an exciting coil for energizing said secondary circuit, two circuit breakers for the exciting coil, one comprising a vibratile element, a single switch adapted to coöperate with both circuit breakers and to render either electrically operative or inoperative, and means 115 dependent on the speed of the engine for operating said switch to render the vibratile circuit breaker inoperative. 120

4. In an ignition system for combustion engines, a secondary ignition circuit, an exciting coil for energizing said secondary circuit, two circuit breakers for the exciting coil, one comprising a vibratile element, and means for maintaining a shunt circuit 125 130

- around the contacts of the other circuit breaker to render it inoperative while the vibratile circuit breaker is operative to make and break current through the exciting coil.
5. In an ignition system for combustion engines, a secondary ignition circuit, an exciting coil for energizing said secondary circuit, two circuit breakers for the exciting coil, one comprising a vibratile element, and 10 a single switch for establishing a shunt circuit around the contacts of either circuit breaker.
6. In an ignition system for combustion engines, a secondary ignition circuit, an exciting coil for energizing said secondary circuit, two circuit breakers for the exciting coil, one comprising a vibratile element, and 15 a switch for establishing a shunt circuit around the contacts of either circuit breaker 20 and simultaneously connecting the other circuit breaker in circuit with the exciting coil.
7. In an ignition system for combustion engines, a secondary ignition circuit, an exciting coil for energizing said secondary circuit, two circuit breakers for the exciting coil, one comprising a vibratile element, a single switch coöperating with both circuit breakers and adapted to render either circuit breaker electrically operative or inoperative, and means for preventing movement of said switch to place the vibratile circuit breaker in operative circuit while the contacts of the other circuit breaker are in closed position.
35. 8. In an ignition system for combustion engines, a secondary ignition circuit, an exciting coil for energizing said secondary circuit, two circuit breakers for the exciting coil, one comprising a vibratile element, a single switch coöperating with both circuit breakers and adapted to render either circuit breaker electrically operative or inoperative, means for operating said switch to 40 render the vibratile circuit breaker inoperative, and electromagnetic means for holding said switch in said last named position while the contacts of the other circuit breaker are in closed position.
9. In an ignition system for combustion engines, a secondary ignition circuit, an exciting coil for energizing said secondary circuit, an engine operated circuit breaker for the exciting coil, a vibratile circuit breaker for said coil, a timer switch operated by the engine and in circuit with the vibratile circuit breaker, a switch for rendering the vibratile circuit breaker inoperative and connecting the engine operated circuit breaker in operative circuit with the
- exciting coil, and electromagnetic means for preventing movement of the last named switch while contacts of the timer switch are separated.
10. In an ignition system for combustion engines, a secondary ignition circuit, an exciting coil for energizing said secondary circuit, two circuit breakers for the exciting coil, one comprising a vibratile element, a single switch coöperating with both circuit breakers and adapted to render either circuit breaker electrically operative or inoperative, and means for preventing movement of said switch during a portion of each engine cycle.
11. In an ignition system for combustion engines, a secondary ignition circuit, an exciting coil for energizing said secondary circuit, two circuit breakers for the exciting coil, one comprising a vibratile element, a single switch coöperating with both circuit breakers and adapted to render either circuit breaker electrically operative or inoperative, and electromagnetic means controlling said switch, said means comprising a coil in circuit with the movable element of the switch when in its attracted position.
12. In an ignition system for combustion engines, a secondary ignition circuit, an exciting coil for energizing said secondary circuit, a dynamo electric machine driven by the engine, two circuit breakers for the exciting coil, one comprising a vibratile element, a single switch coöperating with both circuit breakers and adapted to render either circuit breaker electrically operative or inoperative, electromagnetic means controlling said switch, said means comprising a coil in circuit with the movable element of the switch when in its attracted position and a coil in circuit with the dynamo electric machine.
13. In an ignition system for combustion engines, a secondary ignition circuit, an exciting coil for energizing said secondary circuit, a dynamo electric machine driven by the engine, two circuit breakers for the exciting coil, one comprising a vibratile element, a switch adapted to render either circuit breaker electrically operative, and means governed by the current generated by the dynamo for operating said switch.
- In testimony whereof, I have hereunto set my hand and affixed my seal in the presence of the two subscribing witnesses.
